(57) **CLAIM**

The ornamental design for a portion of a display screen with a graphical user interface, as shown and described.

DESCRIPTION

FIG. 1 is a front view of a portion of a display screen with a graphical user interface.

FIG. 2 is a second embodiment thereof.

FIG. 3 is a third embodiment thereof.

FIG. 4 is a fourth embodiment thereof; and,

FIG. 5 is a fifth embodiment thereof.

The broken lines illustrating a portion of a display screen form no part of the claimed design.

1 Claim, 5 Drawing Sheets
